TABLE I

Filed Jan. 26, 1922

2 Sheets-Sheet 2

UNITED STATES PATENT OFFICE.

SIDNEY YOUNG SULLIVAN, OF NEWARK, NEW JERSEY.

TABLE.

Application filed January 26, 1922. Serial No. 531,866.

To all whom it may concern:

Be it known that I, SIDNEY YOUNG SULLIVAN, a citizen of the United States, and resident of Newark, in the county of Essex and State of New Jersey, have invented certain new and useful Improvements in Tables, of which the following is a specification.

This invention relates to tables, particularly kitchen tables. The object of the invention is to provide a generally improved kitchen or work table containing many novel and useful features of construction, whereby a more useful sanitary and inexpensive table may be provided.

One object of the invention is to provide a table which may be shipped in knock down condition and assembled without the use of screws and nails. Another object is to provide a wooden table having a metal or enameled top and provided with means for preventing the metal top from sliding off the table and also provided with means for preventing warping or twisting. The invention provides other features of usefulness embodied in the construction of the table. These will, however, be far better understood from the following specification taken in connection with the accompanying drawing in which—

Figure 1 is an isometric perspective view of a table embodying my invention, with parts broken away and other parts removed. The top of the table is shown in dotted outline and only the frame construction itself is illustrated.

Figure 2 is a view of the upper part of the table taken substantially on the line 2—2 of Figure 1.

Figure 3 is a view taken on line 3—3 of Figure 2.

Figure 4 is an end view of the table without the legs and other parts.

Figure 5 is a perspective view of a constructional detail.

Figure 6 is a view showing a certain part made of metal instead of wood.

Figure 7 is a plan view of a corner of the assembled table frame ready to receive a leg.

Figure 8 is a view of the parts shown in Figure 7 with the leg in position and looking in the direction of arrow 8 in Figure 7.

Figure 9 is a view looking in the direction of arrow 9 in Figure 7.

Figure 10 is a sectional view through a corner of the table and leg showing a modification.

Figure 11 is a plan bottom view of the table shown in Figure 1 with parts broken away and illustrating a modification.

Figure 12 is a sectional view on line 12—12 in Figure 11.

Figure 13 is a view of a portion of the table showing the flour bin.

Referring first to Figures 1 to 5, inclusive, my improved table comprises a table frame consisting of the front side 1, the back side 2, left end piece 3 and right end piece 4. The four frame pieces are assembled to form a regular table frame by corner fastening means to be presently described.

The two sides are each provided with two spaced and aligned recesses of the character shown in Figure 5, wherein the recess is marked 5 and is in the nature of a notch cut into the wood and formed with a ledge 6.

Into these recesses 5 are placed two parallel top supports 7 and 8, which are of the same width as the said recesses so as to fit into the same. Each support ends in an overhanging arm 9 and is of the shape well illustrated in Figure 3 where it will be seen that the support has a body portion 10 of the same height as the side 1, which body portion is cut away as at 11 towards the back side 2. In order to fit firmly into the said recesses 5, the supports 7 and 8 have small shoulders 12 which rest upon the recess ledge 6 aforesaid. In this manner the supports are firmly held against downward pressure and cannot move sideways.

The front side 1 has a drawer cut out 13 and a pastry board cut out 14, the latter being formed by cutting away the frame 1 between the arms 9, 9. The insides of the top supports 7 and 8, that is the opposed faces thereof, are each provided with a way or groove 15, in which the drawer 16 slides in the usual manner, and a way or groove 17 adapted to receive the pastry board 18, which is shown only in Figure 2.

The right end frame 4 has two recesses 20, Figure 2, which recesses are similar to the recesses 5 aforesaid. In the said recesses 19 and 20 and extending between the support 8 and the side 4 there are inserted two cooperating block groove pieces 21, 21 provided with grooves 22, Figure 3, in which

a block support 23 is adapted to slide and move out beyond the side 4, through a cut 24. The block support has hinged thereto a meat chopper block 25. A keel 26 acts 5 as a stop for the outward movement of the block support 23 and also prevents it from rattling, said keel also having a tongue 27 movable in the side 4. A tongue and recess 10 in the block 25 and the support 23 respectively and indicated at 28 in Figure 2 prevent lateral movement of the block on the support.

As shown in Figure 2 the block 25 may be pulled out, turned over on the support 23 and used to support a food chopper or other similar implement substantially flush with the metal top 30, it being a well known fact that such implements cannot be supported on the metal top itself.

20 When not required, the block 25 is swung down on the support 23 and pushed in under the top.

If desired the supports 7 and 8 may be made deeper as indicated in Figure 13, 25 where they are shown provided with a third way or groove 31 parallel to the ways 17 and 15 aforesaid. The ways 31 may be used for the support of a flour bin 32 to slide in under the table in the grooves 31 in the 30 usual manner.

The sides 33 of the flour bin, one only is shown, may be cut symmetrically out of a square piece of wood as a matter of economy and whereby space at 34 is provided 35 for the knees of a person sitting down at the table. The flour bin has preferably an all metal bottom 35.

In order to assemble the pieces 1 to 4 to form a permanent table frame, I provide 40 means as shown in Figures 7 to 9. The said frame pieces are near their ends provided with vertical slits 36, and for each corner I provide a corner plate of metal generally designated by the numeral 37. Each 45 plate is of a height equal to the height of the frame pieces, and each plate comprises a leg supporting portion 38 and frame supporting portions 39, 39, all of which are integral. The said portions 39 have vertically disposed jaws 40 adapted to be forced 50 into the slits 36 in the sides of the frame pieces. In addition each plate has two toothed claws 41, each of which is adapted 55 to be hammered into the edge of the two adjoining frame pieces. The plate leg portion 38 has jaws 46 adapted to engage slits 47 in the legs 60.

The plate 37 is further provided with an integral leg and top supporting bar 42 having a prong 43 adapted to enter the leg, and a lug 44 with bolt 45 engaging the table top.

The plates 37 are used as shown in Figures 7, 8 and 9, in which it will be seen that

the plates are hammered first into the sides 65 as in Figure 7—where the sides are shown inverted or bottom edge upwards, while the leg is indicated in dotted outline. And it will be noted that the adjoining ends of the frames are held firmly in proper relationship by the plate 37 which engages both the sides of the frames as well as the bottom edge (uppermost in Figure 7). Also, that in this position the leg 60 is ready to be slid 70 into proper position, in that the leg is provided with recesses 48 to slide over the ends of the frame. As the leg slides downward into position, the slits 47 in the leg fit over the jaws 46 in the plate 37, and the leg is finally hammered home down upon the 75 prong 43.

When all four legs are in position, they and the frame are placed right side up as in Figures 8 and 9. Thereafter the top 30 is laid on the frame and spanned or wedged 80 firmly in position by screwing the bolts 45 outward into the corners of the top. In addition the top 30 is held firmly by the arms 9, which are tightly wedged against the overhanging side flange of the top. And the upwardly curved upper surfaces of the members 7 and 8 prevent sagging of the top as will be readily understood from an 85 inspection of Fig. 3.

In some cases it may be deemed necessary to have additional holding means for the leg in which case a bolt 49 may be passed through the leg, Figure 10, and engage, but not pass through, a non-turnable head 50. When thus placed in position, the leg is slid 100 down into place as above described and the bolt 49 will slide into position through a slot 51 provided in the plate leg portion 38, see Figure 10. The bolt 49 may, of course, also be placed in position after the 105 leg is in position on the frame.

Figures 11 and 12 show a modification in which a top end board 52 is fitted tightly within the end 53 of the top. The corner fastening means are plates 54 screwed fast to the frames and the leg fastening means are bolts 55 secured to the leg 60 by passing through them from the outside and having non-turnable integral heads 56. In positioning the legs, they are slid downward as 115 before, with the bolts sliding in slots 57 in the plates 54, after which the nuts 58 are tightened. Screws as 59, Figure 12, may be screwed through the table frame pieces and into the top end boards 52 to unite the frame 120 and the top.

Figure 11 shows a means 65 for fastening the drawer 16 from the rear against accidental opening, said means being for instance a pivoted hook as shown, and said hook 65 may also serve as a means of keeping the legs 60 in knocked down position as shown in Figure 3.

Figure 6 shows the supporting boards 7 and 8 stamped and bent from a sheet of metal 70.

Figure 1 shows how a foldable shelf 71 may be provided to support a pail or the like. The shelf is pivoted in the legs 60 at 72 and is supported by a chain 73 when folded down, and held in upright closed position by a catch 74. 75 is a recess to position the pail. The shelf is very convenient when cleaning the table to sweep or wash off the top.

It will be noted from the foregoing that the table according to this invention may be assembled without screws or nails, is easily set up and taken apart for shipping purposes.

The plates 37 hold both the corner and the legs firmly as well as providing the required fastening means at 44-45 for securing the top.

Changes in the detailed construction may of course be made without departing from the principle of the invention and the scope 25 of the appended claims.

I claim:-

1. The combination of a wooden table frame, upwardly curved top supporting members fitted into said frame, a metal top 30 adapted to rest upon said upwardly curved top supporting members and holding members for securing said frame and top together at the corners thereof.

2. The combination of a wooden table frame and legs, top supporting members secured to said frames by fitting into recesses 35 therein, a metal top resting upon said top supporting members, the upper surface of which is curved upwardly to prevent said top from sagging and corner securing means 40 adapted to engage simultaneously the said table frame, legs and top to secure said parts together.

3. The combination of table frame members, a metal top therefor having a down turned flange on the edge of said top, corner 45 joining members for said frame and

means in said members adapted to engage the said flange of the top to secure the latter in position on said frame. 50

4. In a table, the combination of transverse top supporting members provided with a cut out portion adapted to receive the legs of said table in knocked down position and a drawer locking means for keeping said 55 legs positioned as aforesaid.

5. The combination of table frame members, a metal top therefor having a turned down flange on the edge thereof, corner joining members for said frame and means 60 in said members adapted to engage the said top flange at the corner thereof, said means extending diagonally with relation to the said table frame.

6. The combination of table frame members, a top therefor, means for joining said members to form a rectangular table and secure the said top thereto comprising for each corner of said table a plate having integral frame engaging portions and an integral diagonally extending top supporting portion, and means in the latter for adjustably engaging the said top. 65

7. The combination of frame members, leg members and a top, means for joining the 75 aforesaid elements together to form a table comprising a joining plate having integral members for joining the said frame members and legs at the corners of the table and for engaging the said top at the corners 80 thereof.

8. A table frame comprising a front and a back, and two ends, means for joining said elements to form a rectangular table frame, table top supporting members secured to the 85 said front and back, a food chopper block for said table and supporting means for said block secured between one of said table top supporting members and one of said sides. 90

Signed at Newark, in the county of Essex 90 and State of New Jersey this 21st day of January, A. D. 1922.

SIDNEY YOUNG SULLIVAN.
